UNITED STATES PATENT OFFICE

GEORGE R. WATSON, OF WATERLOO, IOWA, ASSIGNOR TO ARMSTRONG MANUFACTURING COMPANY, OF WATERLOO, IOWA

WELL-DRILLING APPARATUS

Application filed November 9, 1928. Serial No. 318,207.

My invention relates to improvements in well drilling apparatus, and the object of my improvement is to supply an elastic cushioning device for the sheave-block of a well 5 drilling machine to support it and the tool carrying cable reeved thereon with the pendant parts thus relieved from excessive tension and rigidity while the machine is in operation.

- 10 This object I have accomplished by the means which are hereinafter described and claimed, and which are illustrated in the accompanying drawings, it being understood that changes in the precise embodiment of 15 invention herein disclosed can be made within the scope of what is claimed without departing from the spirit of the invention.

In said drawings, Fig. 1 is a front and Fig. 2 a side elevation of the upper part of 20 the mast or derrick of a well drilling machine as equipped with my improved cushioning device for the sheave-block and tool-carrying cable. Figs. 3 and 4 are elevations of a modification of the device. Fig. 5 is a plan of one 25 of the apertured elastic cushions of the said device, on a larger scale. Fig. 6 is a vertical central section of one of said elastic cushions as mounted between a pair of rigid plates, the dotted lines indicating the changed shape of 30 the cushion when under compression. Fig. 7 is a plan of the rigid top member of said cushioning device. Fig. 8 is a horizontal section of the mast or derrick taken on the broken line 8—8 of Fig. 3. Fig. 9 is a dia- 35 grammatic elevation of an operating means of a well drilling machine and of the top part of the derrick thereof, showing the manner of mounting the cable upon the derrick sheave and as supported upon said cushioning de- 40 vice.

In the last-mentioned figure 13 denotes 45 the swinging arm of the well drilling machine which lifts and drops the cable 11 alternately with the heavy depending drilling tool 12. The cable is progressively paid out during the drilling of the well-hole by said tool in a well-known manner not illustrated, and runs about a sheave 14 on the arm 13 and thence upwardly over a sheave 8 mounted 50 rotatably in alined bearing apertures 10 in

a block 7 which is supported upon an elastic cushioning device composed of alternated rigid plates 4 and soft rubber cushions 1.

This cushioning device is mounted and supported upon the relatively fixed supporting mast or derrick 6 by means of a stem passed upwardly from the derrick rigidly through alined central apertures in said pile of plates and cushions. 55

The arm 13 is swung to and fro by means of a rotary shaft 17 with crank 16, and a connecting-rod 15 connected between said crank and said arm. 60

Referring now to the other figures, in which the details of the invention are more specifically illustrated, the derrick is composed of laterally spaced substantially vertical channel bars 6 rigidly connected by a yoke 23 in Fig. 1, and by a similar yoke 19 in Fig. 3, and lower down by transverse bars as at 26 and 27. 65 Referring to said Figs. 3 and 4, the numeral 18 denotes plates riveted opposite each other along one face of each channel bar 6 and the numeral 28 denotes (Fig. 8) angle bars riveted to the inner faces of the channel bars 70 to thus provide vertically disposed slideways for a pair of wooden slide-beams 7 placed in contact with the inner faces of the channel bars. The upper ends of the beams 7 have notched seats 10 to removably receive the 75 ends of a cross shaft 9 carrying a sheave 8 between the channel bars. Upon the front and rear faces of the blocks 7 are fastened the upright members of U-shaped plates 24, and from these depend a part 21 having a 80 discoidal part 20 and a centrally depending stem 5. This stem 5 is loosely slidably seated in alined central apertures 2 of a cushioning device below the part 20 and comprising a 85 pile of alternated rigid plates 4 and soft elastic rubber cushions 1 between the plate part 20 and a bottom plate part 22, the latter forming part of a casting having curvate lateral projections 23 which are riveted to the channel bars 6. 90

The soft rubber discoidal cushions 1 preferably have a plurality of circular apertures 3 lengthwise through them arranged concentric with the central aperture 2. 95

Referring to Figs. 1 and 2, the same princi- 100

ple of construction and function has been employed, but modified, as the top yoke 23 has an integral discoidal part or plate upon which are superposed the alternated plates

5 4 and cushions 1 with terminal top plate 20, the latter having a tubular stem as an abutment for a nut 30, the latter being adjustably mounted on the threaded upper end of the stem 29 which is loosely mounted within the 10 central alined apertures 2 of the pile as heretofore described. However, the lower end part of the stem 29 is also threaded to receive a nut 31 bearing against a tubular abutment depending from the lower plate 22, and this 15 abutment part has arcuate members which are riveted to and between the members of the inverted U-shaped plates 24.

Either modification may be used at option or choice of the purchaser of the machine, for 20 their functions are identical.

It will be noted that said Fig. 6 displays in dotted lines the approximate shape of each discoidal rubber cushion 1 while under compression of the weighty cable 11 and drilling 25 device 12. When the tool has attained a depth of several thousand feet in a drill hole, the cable, whether of metal or otherwise hangs with great weight upon the sheave 8. A metal cable has no inherent lengthwise 30 elasticity, so that without the use of some elastically cushioning device therefor, the cable and tool may be damaged, and the operation of the tool is imperfect, as no rebound to any extent occurs when the tool 35 is dropped, which if present aids the work of drilling. My pile of cushioning disks 1 gives the required elasticity to the cable action, and the stress of compression is equally distributed among the several disks, 40 and also throughout the different parts of each disk, so that there is no inequality of action and use, which conduces to longevity of the disks, and more regular action thereof.

Having described my invention, what I 45 claim as new, and desire to secure by Letters Patent, is:

1. In combination, a relatively fixed support, a resilient device mounted thereon and comprising a pile of alternated centrally 50 apertured rigid plates and soft rubber cushions, said sheave-block having a threaded shank passed through the central apertures of said pile and adjustably secured thereto to be resiliently supported thereon.

55 2. In combination, a relatively fixed support, a resilient device mounted thereon and comprising a pile of alternated centrally apertured rigid plates and soft rubber cushions, the cushions having a plurality of longitudinal apertures around their central apertures, and said sheave-block having a threaded shank passed through said central apertures, and means for adjustably securing said 60 65 sheave-block shank to a terminal rigid plate

of said pile to resiliently adjustably support the sheave-block upon said pile.

In testimony whereof I have affixed my signature.
